UNITED STATES PATENT OFFICE.

MELVIN E. DONALLY, OF BROOKLYN, NEW YORK.

BOTTLE-WASHING MACHINE.

SPECIFICATION forming part of Letters Patent No. 555,598, dated March 3, 1896.

Application filed June 1, 1895. Serial No. 551,350. (No model.)

To all whom it may concern:

Be it known that I, MELVIN E. DONALLY, of the city of Brooklyn, county of Kings, and State of New York, have invented certain new and useful Improvements in Bottle-Washing Machines, of which the following is a specification, reference being had to the accompanying drawings, forming part hereof.

This invention relates particularly to machines for rapidly and effectively cleaning the exteriors of bottles, cans or other like articles, and incidentally also to devices which may be used with such machines to clean the interiors of bottles or other like articles.

The object which I have had in view has been to produce a machine in which the bottle or other article to be cleaned shall be subjected to a rubbing or scraping or brushing so thorough as to remove from its surface any foreign matter, whether it be dirt or a label previously pasted thereon, and at the same time to accomplish this result without causing breakage or any other injury of the bottles or cans or other articles being cleaned. Furthermore, I have sought to devise a machine which shall be capable of operating efficiently upon bottles or other articles which vary more or less in size without requiring adjustment or manipulation of the parts of the machine. I have also in view means for releasing the bottles or other articles in succession, whereby the capacity of the machine is increased and at the same time the danger of breakage is reduced. The various features of improvement, however, will be more fully explained hereinafter.

The machine which I have represented herein as an embodiment of my invention is particularly designed for the cleaning of bottles, but it will be readily understood that with certain obvious changes in form the machine will be equally well adapted for the cleaning of jars or cans or other articles of like character.

In the drawings, in which an embodiment of my invention is illustrated, Figure 1 is a front elevation of a bottle-washing machine. Fig. 2 is a vertical central section thereof, the transmitting-gears at the right being shown in elevation. Fig. 3 is a plan view thereof, a portion of the upper ring of the bot-

tle-carrier being broken away to show parts beneath and many parts which would otherwise appear being omitted in order to avoid confusion. Fig. 4 is a horizontal section on the plane indicated by the line $\alpha\alpha$ of Fig. 2, with the devices for holding the upper ends of the bottles removed and with many parts below the plane of section omitted in order to avoid confusion. Fig. 5 is a detail view, partly in section and partly in elevation, showing the devices for holding the bottle in the carrier and other parts associated therewith.

In the machine represented in the drawings the supporting-framework comprises a suitable base A, posts or standards A' A² erected thereon, an annular plate or table A³ secured to said standards at a suitable height above the base, and a post or bracket A⁴. A vertical shaft B (see Fig. 2) has a bearing a at its lower end in the base A and another bearing in the head a' of the post or bracket A⁴, which is erected upon the base A.

To the shaft B above the head or bearing a' is secured a drum or shell C, which, in the particular mechanism shown, constitutes a carrier for one of the two series of brushes or rubbing or scraping devices which act upon the exteriors of the bottles.

The bottles or other articles to be cleaned are received in the machine shown by a rotary carrier D, which is supported concentric with the brush-carrier C before referred to. As represented in the drawings, (see particularly Fig. 2,) the bottle-carrier D is supported in part by arms d from a hub d', which has a bearing on the head a' of the bracket A⁴, and in part by antifriction-rollers d² d², which travel upon a track d³ supported by the bracket A⁴. An annular plate or table D', formed with or carried by the arms d, has connected thereto by sleeves d⁴ and tie-rods d⁵ an annular plate D², this construction forming a rigid frame on which the bottles are carried. A third annular plate or bar D³ is supported by the sleeves d⁴ at a suitable height above the lower plate or table D', and is preferably made adjustable thereon according to the height of the bottles or other articles which are to be supported between it and the plate or table D'. The bar D³ is represented as

connected by arms d^6 to a hub d^7 , which receives the shaft B and is supported in part by an adjustable collar d^8 on said shaft.

Preferably the brush-carrier C and the bottle-carrier D are rotated in the same direction, but at different velocities. For this purpose the shaft B in the construction shown has secured thereto a bevel-gear b , which is engaged by a bevel-pinion b' carried by the main driving-shaft B' which is supported in suitable bearings on the base A. (See Figs. 1 and 2.) The carrier D, likewise in the construction shown, has secured thereto or formed therewith a bevel-gear D⁴, which is engaged by a bevel-pinion b^2 carried by a counter-shaft B². The latter is supported in a suitable bracket A⁵ carried by the base A, and has fixed thereon a large gear b^3 which is engaged and driven by a pinion b^4 on the driving-shaft B'.

The driving mechanism just described provides for a slow movement of the bottle-carrier and for a more rapid movement of the brush-carrier in the same direction, and while I prefer that the relative movements of the bottle-carrier and of the movable brush-carrier shall be as described it is to be understood that it is not essential that the movements shall be so related.

The bottle-carrier is adapted to receive the bottles to hold them while they are operated upon by the brushes and to permit their removal as they are brought in succession to or near the point at which they are supplied to the carrier. Provision is also made whereby each bottle may be rotated while it is subjected to the action of the brushes in order that every portion of its surface may be thoroughly cleaned. The particular construction whereby these results may be secured will now be described.

In one of the rings or bars D' or D³, preferably the lower one, so that the bottles may be supported mouth downward for a purpose to be referred to, are mounted bottomless cups or tubular sockets E E, Figs. 1, 2, and 5, each of which is adapted to receive and to hold from lateral displacement the head or extremity of a bottle introduced into it. As it is desirable that the bottles should rotate freely, each socket E is preferably mounted upon ball-bearings. As represented in Fig. 5, the bearing-balls e rest in a groove formed in a sleeve E' secured in the plate D', and the socket E is held in place by a ring e', threaded to engage the sleeve E'. The upper portion of the socket E is represented as having a lining of any suitable material, such as rubber, although such lining is not essential.

Corresponding to each socket E, and supported by the ring or bar D³, is a holder F for the other end of the bottle, which is adapted to press with sufficient firmness against the end of the bottle to hold the bottle from displacement while it is being cleaned. This holder preferably comprises a flexible and elastic disk f, Figs. 2 and 5, carried by

a stem f', which slides freely through a suitable guide in the ring or bar D³, and a spring f² which operates to press the disk against the end of the bottle. This disk f is preferably made of some yielding or elastic material in order that it may conform to the bottom of the bottle held between it and the socket and may rub and clean the same as the bottle is rotated, the disk being held from rotation by any suitable means.

The holder F might be moved by hand to release the bottle at the proper time, but that the operator may be able to work with greater rapidity I prefer to provide automatic means for withdrawing the holder and releasing the bottle. As represented in the drawings, Figs. 1, 2, 3, and 5, the stem f is connected to an arm G, which is pivoted to a hub G', and at its outer end is provided with an anti-friction-roller g to bear upon a cam-track g', (see Fig. 1,) which is supported by the standards A², whereby in the revolution of each arm with the bottle-carrier it is lifted at a certain point in its movement to withdraw the holder and release the bottle.

Any suitable connection between the stem f' and the arm G may be provided, but I prefer that the stem shall be square and pass freely through a slot g² in the end of the arm G, while a pin g³ is passed through the end of the stem and rests on the upper side of the arm, Figs. 3 and 5. This construction permits the holder to adapt itself to bottles of different heights without interfering with the movement of the lifting-arm G, and moreover holds the stem and the disk f from rotation.

As it might happen through inattention on the part of the attendant that the bottle which has been released should fall over and be broken, I have provided an additional guard, which is moved into position to hold the bottle from falling when the latter is released, but does not interfere either with the action of the brushes upon the exterior of the bottle nor with the ready removal and introduction of bottles from and to the carrier. As represented, this guard consists of a light wire framework having parallel sides h h, (see Fig. 1,) which slide freely through apertures in the rings D' and D³, a cross-bar h', (see Figs. 1 and 3,) which rests upon the arm G, whereby the guard is moved with the holder F, and a guard-wire h², (see Figs. 1 and 4,) which is carried by the sides h h and normally rests upon the lower ring or table D', but, when the holder F is raised to release the bottle, is lifted to substantially the position represented in Fig. 1, in which position it will prevent the bottle from falling forward, but will not interfere with the removal of the bottle by the operator nor with the introduction of another in its place.

It will be observed that the described provisions for holding the bottle permit it to be held firmly at both ends, whereby danger of breakage is prevented, permit the bottles to

rotate upon their own axes and enable them to be removed and replaced readily.

The brushes which are adapted to scrape and clean the exterior of the bottles are arranged on opposite sides of the path of the bottles so that they may contact with each bottle on opposite sides thereof. If the bottle-carrier travels or rotates as described, it is preferable that one of the brushes or series 10 of brushes should be relatively fixed or stationary, while the other brush or series supported by a carrier C, as represented, travels or rotates at such a speed or in such a direction with respect to the bottle-carrier as that 15 each bottle in being carried between the two brushes or series of brushes shall be compelled to rotate, whereby every portion of its surface is brought into contact with the brushes.

I have referred to a series of brushes on 20 each side of the path of the bottles for the reason that the brushes may thereby be more conveniently arranged to be movable toward and from the path of the bottles and to adapt themselves to the bottles than if the brush on 25 each side of the path of the bottles were made in a continuous piece. Accordingly I have represented a series of independent brushes K K, mounted upon the movable carrier C, and another series of independent brushes K' 30 K', which are supported in a relatively stationary position.

The brushes may be made of any suitable material and in any suitable form according to the particular nature of the work to be 35 performed; but I have represented them as composed each of a piece of card-clothing k, mounted upon a rigid back k', which is shaped to conform to the path of the bottles and preferably has the end which meets the bottles 40 in the relative movement rounded somewhat. The brushes are made to conform somewhat to the general shape of the bottles by additional blocks k² along their lower edges.

In order that the machine may be adapted 45 for efficient operation upon bottles of different sizes, and in order also that danger of breakage may be reduced, each brush is yieldingly supported upon its carrier, so that it may be pressed normally toward the path of 50 the bottles and may be permitted to yield in the opposite direction. Various devices may be employed for supporting the brushes in this manner. As represented in the drawings, each brush is supported near one end, 55 preferably the forward end, by a swinging arm k³, which, in the case of the inner brushes, is pivoted upon the shell or carrier C, and in the case of the outer brushes is pivoted upon a bar A⁶, supported upon adjustable collars 60 k⁴ on the standards A' A². Each arm k³ is preferably provided with a stop-finger k⁵, which limits the movement of the brush toward the path of the bottles. The swinging arms are preferably arranged in pairs, one 65 above another, to maintain the brush in proper position. To each brush are applied one or

more springs k⁶, which press the brush normally toward the path of the bottles.

The brushes might be supported by springs alone; but it is preferable to combine with 70 them the swinging arms referred to and the springs are preferably applied near the end of each brush remote from the swinging arm. Obviously each brush will be pressed toward its support by the bottle as it passes between 75 the two opposite brushes and if the forward end of the next brush protruded abruptly into the path of the bottle it might happen that breakage would be occasioned. Accordingly I provide a loose connection between 80 the ends of adjacent brushes, so that as the rearward end of one brush is pressed back by the bottle the forward end of the next brush shall also be pressed back, the mode of supporting the brushes by swinging arms to which 85 the brush is pivoted and by springs facilitating this connection of the brushes. The connection may be made in any convenient manner. I have represented the end of one brush as provided with a fixed finger k⁷, which enters freely an eye k⁸ carried by the next brush. 90

It is desirable that the bottles should be wet during the action of the brushes thereon, and I have therefore provided suitable nozzles L L, which are connected to a water-supply. 95

As I have indicated previously my main object herein has been to provide for the thorough cleaning of the outer surfaces of bottles or other articles; but it is desirable 100 also to provide means for cleaning and rinsing the interiors of the bottles at the same time. In my machine this is easily provided for without adding materially to the mechanism. For this purpose the bearing block or 105 head a' of the bracket A⁴ has an annular channel a² formed therein, while the hub d² has suitable packing-glands above and below the annular channel. A water-supply pipe M is connected to the bearing block or head 110 a' and is adapted to furnish thereto a continuous supply of water. From the hub d² and in line with the annular channel a² radiate a series of pipes m m, each one of which terminates in a nozzle m' in the side wall of 115 the corresponding sleeve E' of the bottle-carrier and below the rotatable socket E, whereby a stream of water is thrown into each bottle during its passage between the brushes. 120

The water may be sufficient to rinse a bottle which has been previously cleaned; but it may be desired also to provide means for rubbing or brushing the inside of the bottle. Accordingly the bottle-carrier D supports in 125 line with each bottle a movable brush N, which is carried by a suitable stem or spindle n and is adapted to be moved into the bottle at a certain time, the brushing being effected not only by the longitudinal movement of the brush, but by the relative rotation of the 130 brush and bottle. In the present machine the bottle is rotated by the means heretofore

referred to and it is therefore unnecessary that the brush N should be rotated. To effect the required longitudinal movement of the brush the stem n is fixed to a sliding frame 5 n', which is guided in holes formed in the web of the gear D⁴, and is pressed normally upward to cause the brush to enter the bottle by springs n². Each frame has a roller n³, which is adapted to travel with the carrier in contact with a fixed cam-track n⁴, which may be so formed as to cause each brush to move twice into and out of the corresponding bottle during each complete rotation of the carrier.

15 In the operation of the machine herein described the bottles are introduced by the attendant one by one into the bottle-carrier at the front of the machine. The bottles are at first held by the wire guard, but as the carrier continues its movement the arm G descends and the bottle is then held firmly in an upright position while being capable of rotating on its own axis. As the bottles are carried between the brushes they are compelled to rotate by the action of the brushes and are thoroughly scrubbed. During the passage between the brushes a stream of water is thrown continuously into each bottle and at intervals the brush N is thrust into 25 the bottle to assist in the cleaning of the interior. As each bottle passes from between the brushes, the arm G rises to release the bottle and at the same time the wire guard K rises to prevent the bottle from falling over 30 while permitting it to be removed readily by the attendant.

It will be obvious that the details of arrangement and construction of the machine shown in the drawings may be varied without departing from the spirit of my invention, and it is therefore to be understood that the invention is not limited to the precise mechanism shown.

What I claim, and desire to secure by Letters Patent, is—

1. The combination with a carrier having upper and lower bars adapted to support a bottle or other like article at both ends with freedom for rotation and driving mechanism 50 for said carrier, of brushes supported in proximity to the path of the bottle and on opposite sides thereof, and means to effect relative movement of one of said brushes with respect to the other and thereby to rotate the 55 bottle as it is carried between the brushes.

2. The combination with a carrier having upper and lower bars adapted to support a bottle or other like article at both ends with freedom for rotation, and driving mechanism

60 for said carrier, of brushes supported in proximity to the path of the bottle and on opposite sides thereof, a movable carrier for one of said brushes and means to drive said brush-carrier whereby the bottle may be caused to 65 rotate on its axis as it is carried between the brushes.

3. The combination with a carrier having

upper and lower bars adapted to support a bottle or other like article at both ends with freedom for rotation, and driving mechanism 70 for said carrier, of brushes supported in proximity to the path of the bottle and on opposite sides thereof, a stationary support for one of said brushes, a movable carrier for the other of said brushes and mechanism to drive said brush-carrier in the same direction as the bottle-carrier but at a greater speed.

4. The combination with a rotary carrier having upper and lower bars adapted to support a bottle or other like article at both ends 80 with freedom for rotation, and means to rotate said carrier, of brushes supported in proximity to the path of the bottle and on opposite sides thereof, a rotary carrier for one of said brushes concentric with the bottle-carrier 85 and means to rotate said brush-carrier in the same direction as the bottle-carrier but at a greater speed.

5. The combination with a carrier and means to hold a bottle at both ends in a vertical position, with freedom for rotation, of a brush, a support for maintaining said brush in proximity to the path of the bottle, devices acting between said brush and its support to press the brush toward the bottle and to permit it to yield in the opposite direction and means to produce relative movement of the bottle-carrier and brush-support.

6. The combination with a carrier adapted to receive a bottle, of a brush, a support for maintaining the brush in proximity to the bottle, a swinging arm connecting the brush to its support and a spring to press the brush against the bottle and to permit it to yield in the opposite direction and means to produce relative movement of the bottle-carrier and brush-support.

7. The combination with a carrier adapted to receive a bottle, of a brush, a support for maintaining the brush in proximity to the bottle, an arm pivoted upon said support and having the brush pivotally attached thereto, a spring interposed between the brush and said support and means to produce relative movement of the bottle-carrier and brush-support.

8. The combination with a carrier adapted to receive a bottle, of a series of brushes, a support for maintaining said brushes in proximity to the bottle, devices between each brush and the support to press the brush toward the bottle and to permit it to yield in the opposite direction, a loose connection from each brush to the next whereby the proximate ends of adjacent brushes are caused to move together and means to produce relative movement of the bottle-carrier and the brush-support.

9. The combination with a carrier adapted to receive a bottle, of a series of brushes, a support for maintaining said brushes in proximity to the bottle, a spring interposed between each brush and its support to press the brush toward the bottle and to permit it to yield in the opposite direction, a loose con-

nection from each brush to the next whereby the proximate ends of adjacent brushes are caused to move together and means to produce relative movement of the bottle-carrier and brush-support.

5 10. The combination with a rotary carrier adapted to receive a bottle and means to rotate said carrier, of a series of brushes, a support for maintaining said brushes concentric with the bottle-carrier and in proximity to the path of the bottle, a spring interposed between each brush and the support to press the brush toward the bottle and to permit it to yield in the opposite direction and a loose 15 connection from each brush to the next whereby the proximate ends of adjacent brushes are caused to move together.

11. The combination with a carrier adapted to receive a bottle, and driving mechanism 20 therefor, of a series of brushes supported at each side of the path of the bottle and in proximity thereto, a support for each of said series of brushes, devices between each brush and its support to press the brush toward the 25 path of the bottle and to permit it to yield in the opposite direction, and a loose connection from each brush of a series to the next whereby the proximate ends of adjacent brushes are caused to move together.

30 12. The combination with a bottle-carrying frame, a spring-pressed holder mounted thereon and adapted to bear against one end of the bottle, a movable guard-frame supported by said bottle-carrying frame and connected to 35 said holder to move therewith and means to withdraw said holder to release the bottle and at the same time to move said guard-frame into position to support the bottle.

13. The combination with a bottle-carrying 40 frame, a spring-pressed holder mounted thereon and adapted to bear against one end of the bottle, a movable guard-frame supported by said bottle-carrying frame and connected to said holder to move therewith and means to drive said bottle-carrying frame, of an arm 45 mounted upon said bottle-carrying frame and having said holder and guard-frame connected thereto and a cam adapted to act upon said arm and thereby to withdraw the holder 50 to release the bottle and at the same time to move the guard-frame into position to support the bottle.

14. The combination with a bottle-carrier

and means to drive the same continuously, of a brush supported by said carrier to move therewith in line with the bottle and means to move said brush longitudinally into the bottle and to withdraw the same at a predetermined time while the carrier continues its movement.

60 15. The combination with a bottle-carrier, of a brush supported by said carrier to move therewith in line with the bottle, means to drive said carrier continuously and a cam adapted to co-operate with a brush-holder to move the brush longitudinally into the bottle while the carrier continues its movement.

16. The combination with a bottle-carrier and means to drive the same continuously, of a brush supported by said carrier to move therewith in line with the bottle, devices to move said brush longitudinally into the bottle and to withdraw the same at a predetermined time, while the carrier continues its movement and means to produce relative rotation of the bottle and the brush.

70 17. The combination with a bottle-carrier and means to drive the same continuously, of a brush supported by said carrier to move therewith in line with the bottle, devices to move said brush longitudinally into the bottle and to withdraw the same at a predetermined time while the carrier continues its movement and means to rotate the bottle in the carrier.

75 18. The combination with a supporting-frame, of a shaft mounted therein, a brush-carrier secured to said shaft to rotate therewith, a bottle-carrier mounted to rotate concentrically with the brush-carrier and having upper and lower bars to support a bottle at 80 both ends with freedom for rotation, means to rotate said bottle-carrier and brush-carriers in the same direction but at different speeds, and stationary brushes supported by 85 said frame on the opposite side of the path of the bottle, whereby the bottles are compelled to rotate as they move with the carrier and are scraped by the brushes at opposite points.

90 This specification signed and witnessed this 100
1st day of May, A. D. 1895.

MELVIN E. DONALLY

In presence of—

W. B. GREELEY,
S. H. IRISH.
